UNITED STATES PATENT OFFICE.

GEORGE WILLIAM KORN, OF LITTLE VALLEY, NEW YORK.

RAZOR-HANDLE.

No. 805,561.

Specification of Letters Patent.

Patented Nov. 28, 1905.

Application filed April 15, 1905. Serial No. 255,673.

To all whom it may concern:

Be it known that I, GEORGE WILLIAM KORN, a citizen of the United States, and a resident of Little Valley, Cattaraugus county, State of New York, have invented certain new and useful Improvements in Razor-Handles, of which the following is a specification.

My invention has for its object to provide a razor-handle readily detachable from the blade, so that the same handle may be used for a number of interchangeable blades without requiring the use of tools to separate the handle from the blade.

The invention will be fully described hereinafter and the features of novelty pointed out in the appended claims.

Reference is to be had to the accompanying drawings, in which—

Figure 1 is a plan of a complete razor comprising my improved handle. Fig. 2 is a face view thereof, and Fig. 3 is an inside view of one of the handle-sections.

My improved handle comprises two sections A B, which are detachably connected with each other and with the blade C in the following fashion: One of the sections A is provided at one end with a pin A', adapted to pass through the customary hole in the tang of the blade C to form a pivot therefor. The other section B is provided with a corresponding hole or socket B' to receive the end of the pin A'. The two sections A B are made of sheet metal or other suitable elastic material and are bent toward each other at the end opposite to that at which the blade C is pivoted. These bent end portions A² B² are arranged to be in contact with each other when the handle - sections are assembled. The end portion A² is provided with a pin A³, having an enlarged head A⁴, and the end portion B² has an inwardly-directed keyhole-slot B³. The wide end of this slot is of sufficient size to allow the head A⁴ to pass; but the narrow part of the slot is only large enough to receive the body portion of the pin A³. Each of the handle-sections has an outwardly bent or stamped portion A⁵ and B⁴, respectively, the purpose of which is to give stiffness to that portion of the section, while having the ends elastic, and particularly the ends A² B².

In applying the handle to a blade the pin A' is passed through the pivot-hole of the blade, and then the section B is applied. The ends A² B² are thereupon bent or sprung toward each other, so as to bring the head A⁴ of

the pin A³ into the keyhole-slot B³. As soon as the handle-sections are released the elasticity will cause the pin A³ to assume its normal position at the narrow end of the slot B³. The parts will be held firmly against accidental separation; yet whenever it is desired to put in a new blade a simple inward pressure on the end B² will bring the head A⁴ to the wide portion of the keyhole-slot B³, thus allowing the razor to be taken apart.

It will be understood that I rely on the elasticity of the handle-sections, together with the pin A³ A⁴ and keyhole-slot B³, to keep the razor normally in its assembled condition.

Various modifications may be made without departing from the nature of my invention.

I claim—

1. The combination, with the blade, of a handle consisting of two separable sections adapted to receive the blade between them, a pivot-pin connecting the said handle-sections and the blade at one end, a pin secured to one of the sections at the other end and provided with an enlarged head, the corresponding end of the other section being provided with an inwardly-extending keyhole-slot, and each section having its central or body portion bent outwardly to stiffen such portion, while the elastic end portions on which said keyhole-slot and its pin are located, are bent toward each other.

2. The combination, with the blade, of a handle consisting of two separable sections adapted to receive the blade between them, a pivot-pin connecting the blade and handle-section at one end and a pin-and-keyhole-slot connection at the other end of the handle sections, at least one of the said section-s being elastic so as to normally keep the pin-and-keyhole-slot connection against accidental separation.

3. The combination, with the blade, of a handle consisting of two separable sections adapted to receive the blade between them, a pivot-pin connecting the blade and handle-sections at one end, and a detachable locking connection at the other end of the handle-sections, at least one of the said sections being elastic so as to normally keep said locking connection against accidental separation.

4. The combination, with the blade, of a handle consisting of two separable sections adapted to receive the blade between them, a pivot-pin connecting the said handle-sec-

tions and the blade at one end, a pin secured to one of the sections at the other end and provided with an enlarged head, the corresponding end of the other section being provided with an inwardly-extending keyhole-slot, said section having its central or body portion bent outwardly to stiffen such por-

tion, while the elastic end portions on which said keyhole-slot and its pin are located, are bent toward each other.

GEORGE WILLIAM KORN.
